US00D747714S

(12) **United States Design Patent**
Erbeus

(10) **Patent No.:** **US D747,714 S**
(45) **Date of Patent:** **** Jan. 19, 2016**

(54) **WATCH SHAPED COMMUNICATIONS EQUIPMENT**

(71) Applicant: **Sony Mobile Communications AB**, Lund (SE)

(72) Inventor: **Henrik Erbeus**, Lund (SE)

(73) Assignee: **Sony Mobile Communications AB**, Lund (SE)

(**) Term: **14 Years**

(21) Appl. No.: **29/496,863**

(22) Filed: **Jul. 17, 2014**

(30) **Foreign Application Priority Data**

Mar. 7, 2014 (EM) 002420125

(51) **LOC (10) Cl. 14-02**

(52) **U.S. Cl.**

(57) **CLAIM**

The ornamental design for a watch shaped communications equipment, as shown and described.

DESCRIPTION

FIG. 1 is a perspective view of a watch shaped communications equipment showing my new design;

FIG. 2 is a front view thereof.

FIG. 3 is a rear view thereof.

FIG. 4 is a left side view thereof.

FIG. 5 is a bottom view thereof.

FIG. 6 is a right side view thereof; and,

FIG. 7 is a top view thereof.

The broken lines are for the purpose of illustrating portions of the watch shaped communications equipment and form no part of the claimed design.

1 Claim, 7 Drawing Sheets
